UNITED STATES PATENT OFFICE.

WILLIAM E. KEACH, OF FITCHBURG, MASSACHUSETTS.

DESIGN FOR A CLEARER FOR DRAWING-ROLLS.

SPECIFICATION forming part of Design No. 32,829, dated June 12, 1900.

Application filed February 12, 1900. Serial No. 5,018. Term of patent 14 years.

To all whom it may concern:

Be it known that I, WILLIAM E. KEACH, a citizen of the United States, residing at Fitchburg, in the county of Worcester and State of Massachusetts, have invented and produced a new and original Design for Clearers for Drawing-Rolls, of which the following is a specification, reference being had to the accompanying drawing, forming a part thereof, 10 in which an isometrical projection of a clearer embodying my design is shown.

As shown in the drawing, the leading and material feature of my design consists of the clearer-body having the flat longitudinal portion A, the parallel-curved portion B, which 15 forms an upwardly-curved continuation of

said flat longitudinal portion A, the groove C in the face of the clearer interposed between said portions A and B, and the recesses D, formed in the edge of the flat portion A. 20

Having described my invention, what I claim as new, and desire to secure by Letters Patent, is—

The design for a clearer for drawing-rolls as herein shown and described. 25

In testimony whereof I have signed my name to this specification in the presence of two subscribing witnesses.

WILLIAM E. KEACH.

Witnesses:

ALVAH M. LEVY,
CLARENCE E. TUPPER.
